[57] CLAIM

The ornamental design for a taco holder, as shown.

DESCRIPTION

FIG. 1 is a bottom perspective view of a taco holder showing one end of my new design;

FIG. 2 is a side elevational view thereof from the right of FIG. 1;

FIG. 3 is a side elevational view thereof from the left of FIG. 1;

FIG. 4 is a top plan view thereof; and

FIG. 5 is an end elevational view thereof opposite that shown in FIG. 1.
